(57) CLAIM

We claim the ornamental design for a case for a stick-type cosmetic preparation, as shown and described.

DESCRIPTION

This application is based upon PCT No. PCT/JP96/01812, filed June 27, 1996, and published March 20, 1997; which is further based upon Japanese Patent Nos.; 7-262205, filed September 14, 1995; 8-126358, filed April 22, 1996, and 8-150321, filed May 21, 1996.

FIG. 1 is a perspective view of a case for a stick-type cosmetic preparation showing my new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is an opened right side elevation of the design, illustrating a stick-type cosmetic preparation extended from the case, it being understood that the phantom lines are for illustrative purposes only and form no part of the claimed design.
